COMBINED DIAL AND HAND FOR A CLOCK

Ronald B. Kemnitzer, Lisle, Ill., assignor to
Sunbeam Corporation, Chicago, Ill.

Filed May 3, 1973, Ser. No. 357,034

Term of patent 14 years

Int. Cl. D10—07

U.S. Cl. D10—124

FIG. 1

FIG. 2

FIG. 1 is a front elevational view of a combined dial and hand for a clock showing my new design; and
FIG. 2 is a top plan view thereof.

The rear of the dial, not shown, is conventionally flat, plain and unornamented.

I claim:

The ornamental design for a combined dial and hand for a clock, as shown and described.
